UNITED STATES PATENT OFFICE.

LUTHER L. KNOX, OF BELLEVUE, PENNSYLVANIA, ASSIGNOR TO BLAW-KNOX COMPANY, OF PITTSBURGH, PENNSYLVANIA, A CORPORATION OF NEW JERSEY.

GALVANIZING-POT.

1,282,863.

Specification of Letters Patent. Patented Oct. 29, 1918.

Application filed February 4, 1918. Serial No. 215,282.

To all whom it may concern:

Be it known that I, LUTHER L. KNOX, a citizen of the United States, residing at Bellevue, in the county of Allegheny and State of Pennsylvania, have invented a new and useful Improvement in Galvanizing-Pots, of which the following is a full, clear, and exact description, reference being had to the accompanying drawings, forming part 10 of this specification, in which—

Figure 1 is a vertical section of a galvanizing pot embodying my invention;

Fig. 2 is a section on the line II—II of Fig. 1;

15 Figs. 3 and 4 are detail sections taken, respectively, on the lines III—III and IV—IV of Figs. 1 and 2, and showing the parts before welding;

Fig. 5 is a perspective view showing parts 20 of the pot assembled before welding and with the reinforcing band omitted; and

Fig. 6 is a view similar to Fig. 1, but showing a modification.

My invention has relation to galvanizing 25 pots, and is designed to provide a sheet metal pot having a novel construction by which it can be readily made, which will be practically seamless in its finished form, and which will be strong and durable in service.

30 In the construction of my improved pot, I take a sheet metal plate and bend it into U-shape, to form thereby the bottom portion 2 and two of the side walls 3 of the body of the pot, as will be readily seen from Fig. 5. I 35 then take two other sheets or plates of metal 4 and flange their vertical and lower edges, as indicated at 5 and 6, so that they will fit over the open ends of the structure first formed. The flanges 5 lap over the edges of the walls 3, while the bottom flange 6 overlaps the bottom portion 2. The upper edges of the portions 3 and the upper edges of the members 4 may also be flanged outwardly, as shown at 7, to form thereby a top edge flange.

The parts as thus assembled are then welded in any suitable manner, as by the water-gas process, so that the overlapping portions of the members will be homogeneously united with a thickness of the metal at the welds not greatly exceeding the thickness elsewhere.

In this manner, there is provided a practically seamless structure which can be readily

assembled from the metal parts previously 55 bent or pressed to shape.

In service, those portions of the walls of the pot which are adjacent to the metal level in the pot tend to deteriorate and cut away rapidly under the action of the molten bath. 60 I therefore provide those portions of the side walls of the pot which are between the highest and lowest normal levels of the molten bath with a suitable reinforce. This reinforce is preferably in the form of a 65 broad sheet metal band which may be arranged interiorly of the pot, as shown at 8, in Fig. 1, or exteriorly of the pot, as shown at 9, in Fig. 6. This band is preferably formed from a metal plate or sheet bent to 70 shape, with its ends welded, and the band then welded to the body of the pot. It not only acts to unite firmly and to strengthen the previously assembled and welded parts, but it effectively reinforces those portions of 75 the pot which, as above described, are most subject to deterioration in service.

I do not claim broadly herein the provision of a reinforced sheet metal pot, since that forms the subject matter of my copending application Serial No. 215,281, filed February 4, 1918.

I claim:

1. A rectangular sheet-metal galvanizing pot having a bottom, side and end walls, the 85 end walls being formed of sheets having laterally extending projections or flanges, the flanges on the one sheet extending toward the flanges of the other sheet, each of said flanges forming part of the side walls 90 and the bottom of the structure, and a U-shaped sheet overlapping the flanges on the end sheets and secured thereto, said U-shaped sheet forming the other portions of the side walls and the bottom, each joint 95 extending around both sides and the bottom, substantially as described.

2. A rectangular sheet-metal galvanizing pot having a bottom, side and end walls, the end walls each being formed of a single 100 sheet having angular flanges extending therefrom, the flanges on one sheet extending toward the flanges on the other member, a U-shaped sheet overlapping the flanges of the end sheets and welded thereto, the 105 U-shaped sheet forming remaining portions of the side walls and the bottom, said pot having rounded corners at the junctions be-

- 5 between the walls and the junctions between the walls and the bottom, each joint extending around both the side walls and the bottom and at a point slightly beyond where the rounded corners merge into the side walls and the bottom, substantially as described.
- 10 3. A rectangular sheet-metal galvanizing pot having flat side and end walls and a flat bottom, there being rounded corners at the junctions of the walls and the walls and the bottom, each being formed of a flat sheet metal member having angular flanges extending toward the flanges on the other member, and a U-shaped sheet forming the remaining portions of the side walls and the bottom, said sheet overlapping the end members and welded thereto, each joint between the U-shaped sheet and the flanges on the end members being at points where the flanges merge into the flat portions of the side walls and bottom or at a point slightly beyond said points, substantially as described.
- 15 20 25 4. A rectangular sheet-metal galvanizing pot, having a bottom, side and end walls, the end walls each being formed of a single sheet having angular flanges extending therefrom, the flanges on one member extending toward the flanges on the other member, a U-shaped sheet overlapping the flanges of the end members and welded thereto, and forming the remaining portions of the side walls and the bottom, said pot
- 30 35 having rounded corners at the junctions be-

tween the walls and the junctions between the walls and the bottom, each of the joints extending around both the side walls and the bottom and at a point slightly beyond where the rounded corners merge into the 40 walls and the bottom, and the pot having a broad reinforcing band extending around the side and end walls and secured thereto to form a reinforce for the central portion of the pot, as well as a reinforce for the 45 joints, substantially as described.

5. A rectangular sheet-metal galvanizing pot having flat side and end walls and a flat bottom, there being rounded corners at the junctions of the walls and the walls and the bottom, each being formed of a flat sheet metal member having angular flanges extending toward the flanges on the other member, and a U-shaped sheet forming the remaining portions of the side walls and the 50 bottom, said sheet overlapping the end members and welded thereto, the joints between the U-shaped sheet and the flanges on the end sheets being at points where the flanges merge into the flat portions of the side walls 55 and bottom or at a point slightly beyond said points, and the pot having a broad reinforcing band extending around the side and end walls and secured thereto to form a reinforce for the central portion of the 60 pot, as well as a reinforce for the joints, substantially as described.

In testimony whereof, I have hereunto set my hand.

LUTHER L. KNOX.
